UNITED STATES PATENT OFFICE.

GEORGE W. LEIRMAN, OF CLEVELAND, OHIO.

JOINT FOR ARTIFICIAL LIMBS.

No. 834,987.

Specification of Letters Patent.

Patented Nov. 6, 1906.

Application filed May 26, 1906. Serial No. 318,960.

To all whom it may concern:

Be it known that I, GEORGE W. LEIRMAN, a citizen of the United States of America, and a resident of Cleveland, in the county of Cuyahoga and State of Ohio, have invented a new and Reliable Universal Joint for Artificial Limbs, of which the following is a specification.

My invention especially relates to artificial limbs adapted to the pedal extremities and particularly to the joint of the ankle.

The object of my invention is to provide a reliable universal ankle-joint, one that will so closely resemble nature as to almost cover up the visual effect caused by an amputation, to provide a joint that will be elastic and closely simulating the natural action of the foot and instep and having a vertical (limited) motion as well as a centrifugal action and adapted to decline from the normal vertical position to fully the limit of ten degrees or as great an amplification of motion in any direction as is ordinarily enjoyed in the use of the natural foot. These objects and peculiar advantages I will hereinafter explain, so that they will appear obvious to the reader.

By referring to the drawings, which disclose the preferred form of my construction, it will readily be seen how I attain the objects as above, and in which—

Figure 1 is a central vertical section through an artificial leg and foot having my improvement. Fig. 2 comprises two views of a section of felt as used to simulate the articulation of the joint. Fig. 3 is a vertical perspective view of the mechanical joint with its parts in alinement as related to each other, but in an unassembled condition, so as to better show the construction. Fig. 4 serves to show the form of escutcheon-plate used to retain the extremities of the joint parts and prevent them from turning on their vertical axis.

Similar characters refer to similar parts throughout the drawings.

In a more particular perusal of the drawings, in Fig. 1 *a* is a leg portion, and *b* a foot portion, of an artificial limb joined together with my improved joint-bolt, comprising, primarily, three parts *c*, *d*, and *e*. *f* and *g* are two plates adapted to be attached to the leg and foot portions, respectively, as shown, by means of the screws 1 2 3 4 and having a square aperture in the center of each through which the square heads of the joint-bolt are

adapted to neatly fit and free to slide therein. Through lines *A A* is shown a piece of wood *h*, glued to the leg portion and having a square hole coinciding with the square hole in said plate *g* and covering all else of the plate, which is recessed into the said leg. In the rear of said piece of wood *h* I prefer to use a piece of soft rubber *i* as a buffer for the heel action when alighting.

j represents my preferred form of articulation—that of felt—and I prefer to use it in a laminated state. Fig. 2 further shows a section of same.

At *k* is a piece of leather securely glued to the piece of wood *h* and a companion piece glued to the nearest-lying piece of felt to allay friction. The recess *l* in the leg portion serves to allow of a vertical motion to the joint-bolt caused by the impact of the foot and the ground and part of which motion is also taken up by the slotted link *d*. A piece of felt *m* is saturated with heavy oil and is included within the said slot in link *d* and serves to lubricate the pin *n*, serving to attach the link *d* to the lower portion *e* of the joint-bolt. The felt filler is better shown in Fig. 3.

A pin *o* serves to hinge the link *d* to the upper portion of the joint-bolt *c*. The portions *c* and *e* are limited and fastened securely, respectively, as shown, by means of the nuts *p* and *q*, together with accompanying washers. I prefer and have shown a plane surface on the lower extremity of the leg portion and have deviated from likeness to same in the foot portion by adopting a rolling or undulating outline or contour for same, having its highest or pivotal point adjacent to the center of gravity and the joint-bolt. Immediately in the anterior portion I prefer a hollow, as at *r*, thereby allowing for an extra layer of felt to compensate for motion due to the increased radius distance from the joint, while in the posterior portion I prefer a gently-sloping surface, as shown at *s*.

It will appear obvious that the leg may be lengthened out for a limited amount, and thereby compensate for any differentiation of length between the limb worn and the limb retained by the wearer by placing square washers within the recess in the foot occupied by the square part of the portion *e* and directly under same. It is obvious, also, that it is impossible for the foot portion to become out of alinement "fore" and "aft" with regard to the leg, and with all of this

- rigidity still the leg will have a forward to-and-fro motion and a lateral motion, together with a combination of all possible variations of motions in all possible angles of declination from the vertical as enjoyed by the natural joint, while the amplification of motion is controlled at will of wearer by means of the take-up nut p in leg a . In any action of the limb in walking the entire impact of the weight of the wearer is taken up by the felt, the resilient action of which is made possible by the peculiar construction of the joint-bolt, and the jar and noise in walking is reduced to a minimum.
- Having thus described the use and illustrations of my invention, what I claim, and wish to secure by Letters Patent, is—
1. In an artificial limb; the combination of a leg portion and a foot portion together with a suitable intermediate felt portion; of a plurality of metal pieces comprising a universal joint and the intermediate member of said joint adapted to hinge within the terminal members and move freely in all directions; and a slot within one end of the said intermediate piece or link together with a filling of felt, adapted to retain oil as a lubricant for the part and allowing of a yielding
  2. In an artificial limb as described; the combination of a leg and a foot portion, together with an intermediate cushion-section; of a composite, universal, link-joint, composed of two Y pieces or portions, c and e , and a link d , having its two working planes at a right angle one with the other, as shown.
  3. In an artificial limb as described; the combination of a leg and a foot portion, together with an intermediate cushion; of a pair of plates, provided with square holes in same, centrally located; said plates adapted to attach to the leg and foot portion respectively and a universal, composite joint, the outermost shanks of which are square and are adapted to fit in the square holes in the aforementioned plates, all as shown and described.

vertical motion to said joint, all as fully shown and described. 30

2. In an artificial limb as described; the combination of a leg and a foot portion, together with an intermediate cushion-section; of a composite, universal, link-joint, composed of two Y pieces or portions, c and e , 35 and a link d , having its two working planes at a right angle one with the other, as shown.

3. In an artificial limb as described; the combination of a leg and a foot portion, together with an intermediate cushion; of a pair of plates, provided with square holes in same, centrally located; said plates adapted to attach to the leg and foot portion respectively and a universal, composite joint, the outermost shanks of which are square and 40 are adapted to fit in the square holes in the aforementioned plates, all as shown and described. 45

Signed by me at Cleveland, county of Cuyahoga, and State of Ohio, this 23d day of 50 May, A. D. 1906.

GEORGE W. LEIRMANN.
